UNITED STATES PATENT OFFICE.

FRANCIS H. RICHARDS, OF SPRINGFIELD, MASSACHUSETTS.

DESIGN FOR A HEEL-PLATE.

SPECIFICATION forming part of Design No. 17,431, dated July 5, 1887.

Application filed May 26, 1887. Serial No. 239,490. Term of patent 14 years.

To all whom it may concern:

Be it known that I, FRANCIS H. RICHARDS, a citizen of the United States, residing at Springfield, in the county of Hampden and State of Massachusetts, have invented and produced a new and original Design for Heel-Plates, of which the following is a specification, reference being had to the accompanying drawings, forming a part thereof.

Figure 1 is a plan view of the under side of a heel-plate having thereon my design. Fig. 2 is a section in line *a b*. Fig. 3 is a view similar to Fig. 1, showing a variation in the shape of the boot or shoe represented in the design.

The leading feature of my design consists in the outline representation on the under surface of the plate of oppositely-disposed boots or shoes. The plate *B* is preferably of a crescent shape; but other forms may be used. The shoes or boots constituting the design are or may be represented on said plate by means of suitable lines, as the raised lines 3.

My design does not relate to nor consist in the representation on a heel-plate of any particular kind or shape of boot or shoe to the exclusion of another kind or shape thereof. In Fig. 1 of the drawings a pair of low shoes are represented, and they are oppositely disposed and are placed heel to heel. In Fig. 3 there is similarly represented a pair of high-top shoes or lady's boots. In this figure not only is the kind and shape different, but the point of view from which the boots are supposed to be seen is also different, the view in Fig. 1 being somewhat in perspective.

I claim—

The design for a heel-plate herein shown and described, the same consisting of a heel-plate having upon one of its faces the outline representation of a pair of shoes, as set forth.

FRANCIS H. RICHARDS.
